US00D876992S

(12) **United States Design Patent** (10) **Patent No.:** **US D876,992 S**
(45) **Date of Patent:** **** Mar. 3, 2020**

(54) **HANDLEBAR MOUNTED DEVICE HOLDER**

(71) Applicant: **NITE IZE, INC.**, Boulder, CO (US)

(72) Inventor: **Daniel Haarburger**, Boulder, CO (US)

(73) Assignee: **Nite Ize, Inc.**, Boulder, CO (US)

(**) Term: **15 Years**

(21) Appl. No.: **29/628,641**

(22) Filed: **Dec. 6, 2017**

Related U.S. Application Data

(63) Continuation-in-part of application No. 15/640,705, filed on Jul. 3, 2017, which is a continuation of application No. PCT/US2016/012041, filed on Jan. 4, 2016.

(57) **CLAIM**

The ornamental design for a handlebar mounted device holder, as shown and described.

DESCRIPTION

FIG. 1 shows a top perspective view of a handlebar mounted device holder;

FIG. 2 shows a bottom perspective view of the handlebar mounted device holder of FIG. 1;

FIG. 3 shows a top view of the handlebar mounted device holder of FIG. 1;

FIG. 4 shows a bottom view of the handlebar mounted device holder of FIG. 1;

FIG. 5 shows a left side view of the handlebar mounted device holder of FIG. 1;

FIG. 6 shows a right side view of the handlebar mounted device holder of FIG. 1;

FIG. 7 shows an enlarged front view of the handlebar mounted device holder of FIG. 1; and,

FIG. 8 shows an enlarged rear view of the handlebar mounted device holder of FIG. 1.

The broken lines in the drawings illustrate portions of the handlebar mounted device holder and form no part of the claimed design.

1 Claim, 4 Drawing Sheets
